(57) CLAIM

The ornamental design for a wall mount for pull up bar as shown and described.

DESCRIPTION

FIG. 1 is a top, front, left perspective view of a wall mount for pull up bar showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the wall mount for pull up bar show features that form no part of the claimed design.
